UNITED STATES PATENT OFFICE.

LUIS V. LOPEZ S., OF VALPARAISO, CHILE.

SHAKER.

1,085,450.

Specification of Letters Patent.

Patented Jan. 27, 1914.

Application filed February 8, 1913. Serial No. 747,110.

To all whom it may concern:

Be it known that I, LUIS V. LOPEZ S., a citizen of the Republic of Chile, South America, and a resident of Valparaiso, Chile, have invented a new and Improved Shaker, of which the following is a full, clear, and exact description.

The object of my invention is to provide a device for mixing beverages and other liquids, and in which the liquid containers will be disposed horizontally and reciprocated in the horizontal plane instead of in the vertical plane.

A further object is to provide a shaker having an approved construction designed to promote convenience in the use of the shaker, and effect a rapid and thorough shaking of the liquid.

The invention will be more particularly described hereinafter and then pointed out in the claims.

Reference is to be had to the accompanying drawings forming a part of this specification, in which similar characters of reference indicate corresponding parts in both figures.

Figure 1 is a front elevation of a shaker and its actuating means, constructed in accordance with my invention; and Fig. 2 is an end view thereof.

In forming my improved device, a vertical frame 10 is provided, preferably in the form of a plate, and which carries at the rear side at the upper end, a clamp 11, having rearwardly extending upper and lower arms 12, 13, one of which as 12, carries screw clamps 14 threaded in said arm to move the heads 15 toward and from the opposite arm 13, for clamping the device to the edge portion of any convenient supporting table or ledge. A standard 16 is pivoted on the plate A, at the front, to rock in the vertical plane, and the upper end of said standard has arms 17 projecting at opposite sides, one arm terminating in an integral upright 18, and the other arm 17 carrying a slide 19 having a horizontal foot 20, which is clamped to its supporting arm 17 by suitable means, such as a bolt 21 and wing nut 22, the opposed surfaces of the foot 20 and its supporting arm 17 being desirably roughened to give a better engagement.

On the inner face of the upright 18 a conical cup 23 is secured, and a similar cup 24 is secured to the inner face of the upright

19 opposite to and in line with the cup 23, the cups being adapted to receive the bottoms of the usual conical shakers or other equivalent liquid containers, to clamp the said containers in a horizontal position with their mouths against each other, or one within the other as is usual, said containers being shown in dotted lines in Fig. 1, and indicated by the numeral 5.

The pivot 25 of the standard 16 is near the lower end so as to provide a short lower arm 27 and a longer upper arm carrying the cups. To actuate the standard, driving connection is made with the lower arm 27 of the standard. The actuating means comprises a pitman 30, pivoted at the lower end of the arm 27 and connected by a wrist pin 31 to a spur pinion 32 that gears with a spur wheel 33 on the hub 34 of a hand wheel 35, provided with any suitable crank handle 36. The arrangement is such that the turning of the hand wheel 35 will give a rapid movement to the standard for effectively shaking the contents of the containers clamped by the cups 23, 24.

The device may be quickly secured to any convenient support and the liquid containers be quickly and conveniently clamped in place, and as readily removed, and the adjustment of the containers and the operation of the device are effected with convenience and despatch.

Having thus described my invention, I claim as new, and desire to secure by Letters Patent,—

1. A shaker, comprising an upright frame having at the back thereof spaced, rearwardly projecting, parallel members, clamp screws movable in one of said members toward and from the other member, a standard pivoted near its lower end on said frame near one end, at the front of the frame, to provide an upper long arm and a short lower arm, the standard having integral side arms extending from its upper end at opposite sides thereof, one of said arms having a fixed upright at the free end thereof, a slide on the other side arm, said slide having an upright and provided with a foot having sliding connection and clamping engagement with the side arm supporting it, both of said uprights having on their inner faces lateral, conical cups disposed oppositely to and in line with each other, and actuating means connected with the short arm of the standard.

2. A shaker, comprising a frame, a standard pivoted near its lower end to form upper and lower arms, means for actuating the lower end of the standard, the said standard having opposite, projecting, integral side arms on the upper end, one of said arms having an upright provided with a lateral cup, and a slide adjustably secured on the other side arm and provided with a cup disposed opposite to the cup on the fixed upright, the two cups serving to receive the

bottoms of the two liquid containers, to clamp the containers against each other horizontally.

In testimony whereof I have signed my ¹⁵ name to this specification in the presence of two subscribing witnesses.

LUIS V. LOPEZ S.
